CLAIM

We claim the ornamental design for a lock, as shown and described.

DESCRIPTION

FIG. 1 is a front perspective view of a lock showing the new design;

FIG. 2 is a top view of the lock of FIG. 1;

FIG. 3 is a front view of the lock of FIG. 1;

FIG. 4 is a rear view of the lock of FIG. 1;

FIG. 5 is a bottom view of the lock of FIG. 1;

FIG. 6 is a right side view of the lock of FIG. 1;

FIG. 7 is a left side view of the lock of FIG. 1.

FIG. 8 is a front perspective view of a lock showing the new design;

FIG. 9 is a top view of the lock of FIG. 8;

FIG. 10 is a front view of the lock of FIG. 8;

FIG. 11 is a rear view of the lock of FIG. 8;

FIG. 12 is a bottom view of the lock of FIG. 8;

FIG. 13 is a right side view of the lock of FIG. 8; and,

FIG. 14 is a left side view of the lock of FIG. 8.

The portions of the Figures shown in broken lines are for illustrative purpose only and form no part of the claimed design.

1 Claim, 8 Drawing Sheets
